POLYPHASE ELECTROMAGNET STRIP GUIDING AND TENSION DEVICE

Richard S. Baker, Butler, Pa.

Application February 13, 1953, Serial No. 336,744

9 Claims. (Cl. 242—75)

This invention relates to strip coiling apparatus, and more particularly to an improved means for controlling the tension in metal strip as it is being coiled.

A main object of the invention is to provide a novel and improved electromagnetic strip guiding and tensioning device for controlling the tension in conductive strip material as it is being coiled, the improved device being simple in construction, involving relatively simple components, and providing accurately controllable tension on the metal strip being coiled, whether the strip is stationary or is moving.

A further object of the invention is to provide an improved electromagnetic strip tensioning and guiding device which can be employed on conductive strip material having a wide range of width, thicknesses and electrical resistivities, the improved tensioning and guiding device being useful for application to metallic strip of non-magnetic as well as magnetic properties, and eliminating the necessity of using complicated and expensive arrangements of pinch rolls, current regulating devices on the coiler and uncoiler motors, clamps, or brake devices of a mechanical nature, the last-named improvement also eliminating the possibility of scratching or tearing the strip metal as it is coiled.

A still further object of the invention is to provide an improved electromagnetic strip tensioning and guiding device for use in coiling metal strip material; the improved device operating by generating eddy currents in the strip material and by producing motor action which may be utilized either to provide a restraining force on the metal strip in its motion toward the coiler, so that the strip may be tightly coiled by the coiler motor, which may be alternatively utilized in providing balanced guiding forces tending to maintain the strip in its required alignment, or in providing a combination of longitudinal restraining or aiding force on the strip and lateral correcting force to move the strip sideways as necessary to keep the strip edges in proper alignment.

Further objects and advantages of the invention will become apparent from the following description and claims, and from the accompanying drawings, wherein:

Figure 1 is a vertical longitudinal cross sectional view taken through a section of strip metal showing the arrangement of the polyphase electromagnetic tensioning devices above and below the strip.

Figure 2 is a vertical transverse cross sectional view taken through the strip of material of Figure 1, showing the electromagnetic tensioning coils in front elevation.

Figure 3 is a schematic drawing illustrating the coiling and uncoiling rolls of strip and their associated driving motors, shown diagrammatically, and showing the arrangement of the strip tensioning magnets of Figures 1 and 2 relative to the strip and relative to a processing oven or other processing apparatus through which the strip passes.

Figure 4 is a perspective view of one of the laminations employed in the magnet coils of Figures 1 and 2.

Figure 5 is a schematic wiring diagram illustrating the

2

electrical connections of the polyphase coils according to the present invention.

Figure 6 is a front elevational view, partly in vertical cross section, showing a modified set of strip retarding coils according to the present invention, a plurality of polyphase elements being provided on the respective cores of the coils, instead of a single set of polyphase elements on each core as in Figures 1 and 2.

Figure 7 is a transverse vertical cross sectional view taken on the line 7—7 of Figure 6.

Figure 8 is a top plan view showing the arrangement of the strip tensioning coils of Figures 6 and 7 in longitudinal alignment with the strips to provide a longitudinal force on the strips, such as a drag or pinch action.

Figure 9 is a top plan view showing a modified arrangement of polyphase magnetic coils arranged over opposite side marginal portions of the strip to provide lateral forces on the strip for correcting the longitudinal alignment of said strip, the magnets producing forces at right angles to the direction of movement of the strip.

Figure 10 is a top plan view similar to Figure 9 but showing the coils arranged to provide combined longitudinal and lateral forces on the strip to provide a combination of dragging or pinching action together with lateral correcting force on the strip.

Referring to the drawings, and more particularly to Figures 1 through 5 inclusive, 11 designates a section of strip material, such as conductive strip metal which is to be coiled on a roll 12 and which is uncoiled from a roll 13, as shown in Figure 3. The strip material 11 may be either non-magnetic metal, such as aluminum or copper strip, or may be material having magnetic properties, such as steel strip.

As shown in Figure 3, the strip is coiled on the roll 12 by a coiler motor 14 which is suitably connected in any conventional manner to the coiling shaft of the roll 12, and the strip is uncoiled from the roll 13 by an uncoiling motor 15, coupled similarly to the shaft carrying the coil 13. The strip 11 may be passed through a processing oven 16 or other processing apparatus as it is coiled on the roll 12 from the uncoiling roll 13.

Designated generally at 17 is a magnetic strip tensioning device in accordance with the present invention, said device being positioned between the uncoiling roll 13 and the processing device 16, as shown, or between the processing device 16 and the roll 12. The tensioning device 17 may comprise an upper polyphase magnet, designated generally at 18, and a lower polyphase magnet designated generally at 19, the upper magnet 18 being placed above and parallel to the top surface of the strip 11 and the lower magnet 19 being placed below and parallel to the bottom surface of the strip 11 in vertical alignment with the upper magnet 18, as shown in Figure 1. The upper magnet 18 comprises a core 20 supported in any suitable manner in a direction extending longitudinally of the strip 11 and comprising a plurality of longitudinally extending laminations 21 formed with the registering notches 22, 23 and 24, as shown in Figure 4, respective coils 25, 26 and 27 being positioned in said notches and surrounding the core 20, as shown in Figures 1 and 2. The coils 25, 26 and 27 may be generally rectangular in shape and the core 20 may be engaged on the lower arms of the coils, as illustrated. The magnet 19 comprises a similar core 20' having identical laminations 21 and having the respective coils 25', 26', and 27' engaged on the core and extending through the notches in the laminations, the core 20' being engaged with the top arms of the rectangular coils, as illustrated in Figure 2.

As shown in Figure 1, the coil 25 is in vertical alignment with the coil 25', and said coils extend at right angles to the direction of movement of the strip 11.

Similarly, the coil 26 is in vertical alignment with the coil 25' and the coil 27 is in vertical alignment with the coil 27', said coils all extending at right angles to the direction of movement of the strip.

Referring now to Figure 5, it will be seen that the coils 25 and 25' are connected in parallel with the current in the bottom arm of coil 25 flowing in the same direction as the current in the top arm of coil 25' at every instant, the coils 26 and 26' are connected in parallel, with the current in the bottom arm of coil 26 flowing in the same direction as the current in the top arm of coil 26' at every instant, and the coils 27 and 27' are connected in parallel with the current in the bottom arm of coil 27 flowing in the same direction as the current in the top arm of coil 27' at every instant, each of the parallel connected sets of coils being connected to a respective phase of a three-phase alternating current generator 29 in the manner illustrated in Figure 5. As is apparent from Figure 5, the coils 25 and 25' are connected by respective conductors 30 and 31 to one of the output phases of the generator 29, the coils 26 and 26' are connected by the conductors 31 and 32 to another of the output phases of the generator 29, and the coils 27 and 27' are connected by the conductors 30 and 32 to the remaining output phase of the generator 29.

The manner of connection thus illustrated produces a traveling magnetic field which field passes downwardly from the top magnet 18 to the strip 11 to the bottom magnet 19, then around through the core 20' of the bottom magnet 19 and upwardly through the strip 11 to the core 20 of the upper magnet 18. The magnets 18 and 19 thus act as the stator of a polyphase induction motor and the strip 11 acts as a rotor. The magnets produce a mechanical force in the strip because of the eddy currents that flow in the strip. These eddy currents are set up by the motion of the magnetic field along the strip, the same as turning force is produced in the rotor of a commercial polyphase induction motor having a squirrel cage rotor.

The force thus produced may be either in a direction to retard the movement of the strip, whereby the device may be employed as a braking or pinching means, providing a steady force restraining the strip in its motion toward the coil 12, so that the strip may be tightly coiled by the coiling motor 14. Alternatively, the device may be employed to provide an additional pull on the strip 11 to aid the coiling motor 14 in coiling the strip up on the coil 12.

It is also apparent that only a single set of coils may be employed, either positioned above or below the strip 11, to provide the desired retarding or aiding longitudinally force on the strip. In other words, either the magnet 18 or the magnet 19 may be omitted to provide the desired longitudinal force on the strip 11 by the use of only a single magnet. The use of magnets above and below the strip, however, provides a greatly increased resultant force on the strip, as over the use of a single magnet.

To control the current, and hence the force produced on the strip by the polyphase electromagnets, any one of several commercially available systems may be used, for example, the saturable-core reactor control system, series resistor systems of control, or the like. For a three-phase electromagnetic arrangement, such as is illustrated in Figure 5, saturable-core reactors would need to be inserted in series with only two of the three wires supplying the magnets.

When only a single magnet is employed, as for example, either the magnets 18 or 19 above or below the strip 11, a stack of laminations may be employed on the opposite side of the strip to reduce the reluctance of the path of the magnetic flux passing through the strip 11.

Referring now to Figures 6 and 7, the magnet coils may be arranged in a plurality of groups on an extended core, such as the core 40 or the core 41 illustrated in Figure 6. The core 40 carries a plurality of series of coils 25, 26

and 27, the respective coils 25 being connected in parallel with each other, the respective coils 26 being connected in parallel with each other and the respective coils 27 being connected in parallel with each other, and the coils being arranged sequentially along the core 40. Similarly, the lower magnet has the coils 25', 26' and 27' arranged in successive groups and being in vertical alignment with the respective coils 25, 26 and 27 of the top magnet. The groups of coils 25' are connected in parallel, the groups of coils 26' are connected in parallel, and the groups of coils 27' are connected in parallel. The respective groups 25' are connected in parallel with the coils 25 of the top magnet and these are connected to one of the phases of the three-phase generator employed to energize the magnets. Similarly, the groups 26' and 26 are connected in parallel and are connected to another phase of the generator and the groups 27' and 27 are connected in parallel and are connected to the remaining phase of the generator, to provide a traveling magnetic field similar to that described in connection with the form of the invention disclosed in Figures 1 to 5. The action of the device of Figures 6 and 7 is similar to the device illustrated in Figures 1 and 2 except that the forces developed are of larger magnitude because of the larger number of coils and magnetizing turns provided by the magnets. As shown in Figure 7, the strip 11 is arranged between the cores 40 and 41 and longitudinal forces are developed in the strip because of the eddy currents produced in the strip as the strip moves longitudinally through the space between the cores 40 and 41, or when the longitudinal or other motion of the strip has ceased.

In Figures 6 and 7, the top magnet is designated generally by the reference numeral 38 and the bottom magnet is designated generally by the reference numeral 39.

Referring now to Figure 8, the magnets may be arranged with their cores positioned longitudinally of the strip 11 to provide either a drag or pitch action or an aiding action on the strip, as described above in connection with the form of the invention illustrated in Figures 1 to 5. As above explained, the motion of the magnetic field along the strip produces a motor action which provides a longitudinal force on the strip which, in one arrangement, may be employed to retard the movement of the strip, or by reversing the position of the coils may be employed to aid the movement of the strip by providing a force in the same direction as the direction of motion of the strip.

In the form of the invention shown in Figure 9, the polyphase magnets, designated respectively at 38 and 38' may be arranged with their cores extending at right angles to the direction of movement of the strip 11, the core of the magnet 38 and the core of the magnet 38' being in transverse alignment, as shown in Figure 9, and the coils thereof being arranged so that they produce oppositely directed lateral forces on the strip toward the center of the strip. The magnets 38 and 38' are of identical construction and therefore produce equal and opposite actions on the strip when the strip is centered beneath the magnets. If the strip tends to deviate so as to bring a larger proportion thereof beneath one of the magnets than the other, a larger eddy current effect is developed in that portion of the strip having the larger area located beneath a magnet and a correcting force is developed by the motor action between the strip and the magnet which tends to move the strip back toward centered relationship relative to the correcting magnet. Therefore, automatic correcting lateral forces are produced by the magnets as the strip moves from the uncoiling roll 13 to the coiling roll 12.

When the magnets 38 and 38' are arranged so that they produce oppositely directed lateral forces on the strip in a direction toward the edges of the strip, commercially available side-register control apparatus may be used to sense the positions of the edges and to maintain the edges of the strip in their proper path.

As above described, the magnets 38 and 38' may be arranged merely above the strip, or may have corresponding magnets below the strip to increase the magnitude of the correcting forces developed when the strip deviates from its centered position relative to the magnets.

Referring now to the form of the invention illustrated in Figure 10, the correcting magnets, shown at 48 and 48' are supported in any suitable manner in positions extending at equal acute angles relative to the direction of travel of the strip 11. Each of the magnets 48 and 48' may be similar to the polyphase, multiple coil magnet 38, and the cores of the magnets 48 and 48' are similar to the cores 40 and 41. Said cores are oriented in the manner illustrated in Figure 10 so that they extend at equal and opposite acute angles relative to the direction of travel of the strip. Therefore, the traveling magnetic field produces equal and opposite motor actions having components which may be resolved along the direction of movement of the strip and also at right angles to the direction of movement of the strip. Therefore, the magnets 48 and 48' may be employed to provide a combination of either drag or retarding action plus laterally correcting action, or alternatively, a combination of aiding action on the strip plus laterally correcting action. As in the previously described forms of the invention, companion magnets may be employed below the strip in vertical alignment with the magnets 48 and 48' positioned above the strip. Alternatively, respective bundles of laminations may be provided below the strip in vertical alignment with respective magnets 48 and 48' to reduce the reluctance of the respective magnetic paths through the side marginal portions of the strip beneath the respective magnets 48 and 48'.

Any of the previously described devices may be employed in connection with conducting strip materials of a wide range of widths, thicknesses and electrical resistivities. The devices perform best for given sizes of magnets when employed on materials having low resistance per unit of the volume exposed to the magnets. The devices are usable on aluminum, copper or brass strip, in thicknesses from foil to heavy plates. The polyphase magnetic devices of the present invention are superior to the present methods employed in strip tensioning, in that the strip does not have to come into actual contact with the faces of the magnets. With the devices of the prior art, the tension of a strip is controlled either by a complicated and expensive arrangement using pinch rolls and current regulating devices on the coiler and uncoiler motors, or by very crude and ineffective methods, such as clamping the strip between two wooden surfaces, or between surfaces provided with brake lining. The last method is probably the worst of the prior art methods and results in a high waste of the product, since the surface of the strip is scratched and torn by passing through these brake surfaces.

While certain specific embodiments of improved polyphase electromagnetic strip guiding and tensioning devices have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In an apparatus for coiling strip metal of the type having a pair of spaced parallel reels adapted to receive opposite coiled end portions of a strip of metal thereon and means for rotating said reels to move the strip from one reel to the other, a magnetic strip-tensioning device comprising a magnetic core mounted between said reels adjacent the plane of the strip, a plurality of spaced magnetizing windings surrounding said core and a polyphase energizing circuit therefor, said circuit being operable to energize said windings to produce a traveling magnetic field and thereby inducing a mechanical thrust in the strip in the direction of travel of said field.
2. An apparatus as defined in claim 1 in which the windings are positioned substantially parallel to the axes of the reels.
3. An apparatus as defined in claim 1 in which the windings are positioned at right angles to the axes of the reels.
4. An apparatus as defined in claim 1 in which the windings are positioned at a substantial angle to the axes of the reels.
5. An apparatus as defined in claim 1 in which there are provided vertically aligned magnetic cores above and below the plane of the strip and having vertically aligned windings connected in the same phase with each other and operable upon energization to produce said traveling magnetic field extending between said magnetic cores and cutting across said metal strip.
6. An apparatus as defined in claim 5 in which the windings are positioned substantially parallel to the axes of the reels.
7. An apparatus as defined in claim 5 in which the windings are positioned at right angles to the axes of the reels.
8. An apparatus as defined in claim 5 in which the windings are positioned at a substantial angle to the axes of the reels.
9. Tension apparatus for use with strip metal moving means comprising a magnetic device for producing a motor thrust to tension said strip metal and comprising a magnetic core mounted adjacent the plane of and substantially aligned with the strip, a plurality of spaced magnetizing windings surrounding said core and a polyphase energizing circuit therefor, said circuit being operable to energize said windings to produce a traveling magnetic field and thereby inducing a motor thrust in the strip in the direction of travel of said field.
